MULTIPLE DOOR WARDROBE

Arthur L. Leonard, Newcastle, Ind., assignor to
Circle A Products Corporation, Newcastle,
Ind.

Application December 17, 1931, Serial No. 581,661

8 Claims. (Cl. 312—191)

This invention relates to a swinging door construction for a receptacle and the like.

The chief object of this invention is to provide a receptacle such as a wardrobe suitable for school purposes and which includes a substantially open front with a plurality of doors, preferably three or more in number, and arranged in paired door relation, at least two of the adjacent doors being hinged together, all of the doors being movable from aligned position when substantially registering in the plane of the opening of the receptacle into a position substantially transverse thereto and approximately parallel to each other.

Another object of the invention is to so support and connect said doors that opening or closing of any one door will automatically and simultaneously open or close respectively all of said doors.

One feature of the invention consists in the particular mechanical connections between the respective doors, or pairs of doors, whereby the same operate in the aforementioned manner.

Another feature of the invention consists in the addition of a blackboard to one or more of the doors and the means for mounting the blackboard upon the supporting door.

The full nature of the invention will be understood from the accompanying drawing and the following claims and specification:

In the drawing, Fig. 1 is a top plan view of a receptacle, the cover being removed, the doors being shown in receptacle closing position by the full lines and in receptacle exposing or open position by the dotted lines.

Fig. 2 is a similar view of a modified form of invention wherein the same number of doors is similarly connected for identical operation but wherein the doors are arranged in a differently paired arrangement.

Fig. 3 is a vertical sectional view of a wardrobe construction embodying the invention.

Fig. 4 is an enlarged vertical sectional view through a portion of the uppermost mounting and guide for the door.

Fig. 5 is a transverse sectional view taken on line 5—5 of Fig. 4.

Fig. 6 is a top plan view of a bell crank arm operator.

Fig. 7 is a fragmentary view of a link showing in detail a means for adjusting the length thereof.

Fig. 8 is a view in detail of the means pivotally supporting the lower lever arm of a door.

In Fig. 1 of the drawing, 10 indicates the back

wall of a receptacle having an elongated opening at its front, adapted to be closed by a plurality of doors, herein indicated generally by the numeral 11. The receptacle suitably supports on the back wall 10, shelving 12, the same, however, not extending completely from end 14 to end 14 of the receptacle. The purpose of sectionalizing the shelving will be apparent from an examination of Fig. 1. The doors 11 are arranged in Fig. 1 as a plurality of pairs. The four intermediate doors of the six illustrated, are arranged further in pairs, and the second and third and fourth and fifth door are hinged together as at 15. In other words, the adjacent edges of the before mentioned abutting doors are hinged together and are arranged to recede into the receptacle when the doors are opened. The other edges of the doors hinged together in pairs are arranged for substantial abutting engagement with the adjacent door edge when the doors are completely closed.

In Fig. 1 there are six doors illustrated and the end doors are not hinged together to any adjacent door.

In Fig. 2 there are six doors illustrated and the end doors are hinged to the next adjacent door, thereby forming three pairs of doors with the adjacent edges of the adjacent doors hinged together and the other edges of the hinged doors being arranged for substantial abutment with similar edges of adjacent doors.

Each of the doors is mounted upon a pair of lever arms, the upper lever arm being indicated by the numeral 16—see Fig. 3—and the lower being indicated by the numeral 17 and inclined upwardly, as shown. The lower end of the lower lever arm is pivotally supported upon a pedestal 18 positioned within the wardrobe and a considerable distance back from the door when it is closed.

The lever arms 16 and 17 have a coaxial pivotal connection with the door 11 and the same is positioned an appreciable distance from each side edge of the door and intermediate said edges. As illustrated in Fig. 3, the lever arm 17 is connected to the door by a bolt 19, the head 20 of which underlies the bracket 21 carried by the door. The upwardly extending portion of the bolt 19 mounts a pair of adjusting and lock nuts 22. The door 11 mounts an upper bracket 23 that receives the depending arm 24 of the lever arm 16 pivotally suspended and supported by the fixture 25—see Fig. 4.

Each pair of doors, as before mentioned, is

hingedly connected together as at 15. Carried by one of the doors adjacent the hinged connection is a bracket 26 that pivotally mounts a roller 27—see Figs. 4 and 5. Roller 27 rolls in a track-way 28 of channel shape which provides a pair of spaced guides, which trackway extends from the rear of the receptacle toward the front and terminates very near or at the plane of the door opening. Each end of the guide way is closed by 10 the cushion stop members 29, which cushion the extreme opening and closing movements of the doors. If desired—see Fig. 3—an additional door stop 30 may be provided.

To effect simultaneous operation for doors, 15 there is provided an actuating bar or rod 31 that lies substantially parallel to the position of the doors when closed and is reciprocable for door opening and closing and is so arranged that opening of any door or closing of any door will simultaneously open all doors or close all doors respectively. The rod 31 has clampingly associated therewith, as at 31^a, one end of a lever arm 33; the same being operatively associated with the lever 16 of one of the doors of each hingedly connected pair of doors. One of each hingedly connected pair of doors may, if desired, be provided with a link 32 that is of adjustable length, as indicated at 32^a, and which is pivotally connected to the door, as at 34, and the other end of the link is connected as at 35 to the lever arm 36, the same being operatively associated with the lever arm 16 and the lever arm 33 connected to the reciprocating rod or bar 31.

As shown in Fig. 1, the left hand door at the 35 end of the wardrobe is provided with the lever arms 32 and 16; likewise, the right hand door is similarly provided. Of the four intermediate doors, the left hand door of each pair is similarly provided.

40 The left hand door 11, shown in Fig. 1, has associated with the lever mechanism, a lever arm 40 that is adjustably secured as at 41 to an offset member 42, in turn adjustably secured at 43 to the arm 33 of the next adjacent door lever system that is operatively associated with the rod 31. The left hand door 11 supports a lock 44, whereby the door may be locked in the closed position. With this type of arrangement, all of the doors are locked when the left hand door 11 is locked. The left hand door 11 constitutes a master door and all of the other doors will be opened or closed therewith.

55 In Fig. 2 there is illustrated a modified form of the invention in which the hinge connection and door pairing is different from that shown in Fig. 1 and wherein the opening or closing of any door simultaneously secures the opening or closing of any other door. In this form of the invention, similar numerals of the one hundred 60 series indicate parts similar to those shown in Fig. 1. In this form of the invention, the track 128 is exactly perpendicular to the plane of the doors when closed, while in the form shown in Fig. 1, the track 28 is substantially transverse to the plane of the doors when closed. Guide tracks 128 also are of a slightly different character from that shown relative to guides 28 in Fig. 1. In Fig. 2 the tracks are of double width and are not of the full depth of the wardrobe.

70 In Fig. 3 of the drawing, there is illustrated a form of the invention and the same relates to a door structure. In said figure, 50 indicates the blackboard and 51 the peripheral rail or channel frame work thereof. The door and the channel is apertured. Extending through the regis-

tering apertures is a bolt for board anchorage and board position adjustment.

Positioned below the blackboard is a chalk mold 59 suitably secured to the door, and said chalk rail projects beyond the plane of the blackboard so that in the hinging movement of the doors towards each other, said chalk rails serve as stops and prevent the doors from engaging each other when folded, thereby preventing black board injury.

85 In Fig. 6 there is illustrated in greater detail element 36 and its operative association with the cooperating elements.

The invention claimed is:—

1. In a wardrobe, the combination of a pair of doors, upper and lower lever arms for each door and pivotally connected upon a common axis to the associated door and pivotally mounted upon a common axis at their other ends to the ceiling and floor respectively, hinge means connecting the adjacent edges of the doors together for conjoint operation, a pair of spaced guides above the door opening and extending transversely thereof, and a vertically pivoted roller carried by one of the doors above the door opening and mounted between the guides. 90

2. In a wardrobe, the combination of a pair of doors, upper and lower lever arms for each door and pivotally connected upon a common axis to the associated door and pivotally mounted upon a common axis at their other ends to the ceiling and floor respectively, hinge means connecting the adjacent edges of the doors together for conjoint operation, a pair of spaced guides above the door opening and extending transversely thereof, a vertically pivoted roller carried by one of the doors above the door opening and mounted in the guides, and cushion means between the guides at each end thereof for cushioning roller and door movement at each end thereof. 100

110 3. In a wardrobe, the combination of pairs of doors having hinged adjoining edges adapted to recede into the wardrobe when the doors are moved to open position and having the adjoining edges of doors of adjacent pairs in abutting relation when the doors are in closed position, a lever for each door pivotally connected at one end to the door intermediate of and at an appreciable distance from the side edges thereof and mounted upon a pivot within the wardrobe, a reciprocating actuating member normally parallel to the doors when closed, and means connecting said member to one of the levers of each pair of doors. 115

120 4. In a wardrobe, the combination of pairs of doors having hinged adjoining edges adapted to recede into the wardrobe when the doors are moved to open position and having the adjoining edges of doors of adjacent pairs in abutting relation when the doors are in closed position, a lever for each door pivotally connected at one end to the door intermediate of and at an appreciable distance from the side edges thereof and mounted upon a pivot within the wardrobe, a reciprocating actuating member normally parallel to the doors when closed, a link pivotally connected at one end to one door of each pair, a lever arm for each link and pivotally connected to the other end thereof, and means operatively connecting said lever arm with the first mentioned lever and the member. 130

140 5. In a wardrobe, the combination of pairs of doors having hinged adjoining edges adapted to recede into the wardrobe when the doors are moved to open position and having the adjoining edges of doors of adjacent pairs in abutting relation. 150

- tion when the doors are in closed position, a lever for each door pivotally connected at one end to the door intermediate of and at an appreciable distance from the side edges thereof and mounted upon a pivot within the wardrobe, a reciprocating actuating member normally parallel to the doors when closed, a link of adjustable length pivotally connected at one end to one door of each pair, a lever arm for each link and pivotally connected to the other end thereof, and means operatively connecting said lever arm with the first mentioned lever and the member. 5 lever for each door pivotally connected at one end to the door intermediate of and at an appreciable distance from the side edges thereof and mounted upon a pivot within the wardrobe, a reciprocating actuating member normally parallel to the doors when closed, and means connecting said member to each alternate door for simultaneous movement of all doors including a link pivotally connected at one end to each alternate door, and a lever arm for each link and pivotally connected to the other end thereof and operatively associated with the first mentioned of the link connected doors for simultaneous movement of all doors. 80
6. In a wardrobe, the combination of a plurality of and not less than three doors, at least two adjacent doors being hinged at their adjoining edges for recessional movement into the wardrobe when moved into open position, the adjoining edges of the doors including at least one of the paired doors having substantially abutting relation when the doors are closed, a lever for each door connected at one end to the door intermediate of and at an appreciable distance from the side edges thereof and mounted upon a pivot within the wardrobe, means pivotally connecting each lever to its adjacent door, a reciprocating actuating member normally parallel to the doors when closed, and means operatively connecting said member to each alternate door for simultaneous movement of all doors. 90
7. In a wardrobe, the combination of a plurality of and not less than three doors, at least two adjacent doors being hinged at their adjoining edges for recessional movement into the wardrobe when moved into open position, the adjoining edges of the doors including at least one of the paired doors having substantially abutting relation when the doors are closed, a lever for each door pivotally connected at one end to the door intermediate of and at an appreciable distance from the side edges thereof and mounted upon a pivot within the wardrobe, a reciprocating actuating member normally parallel to the doors when closed, and means connecting said member to each alternate door for simultaneous movement of all doors including a link of adjustable length pivotally connected at one end to each alternate door, and a lever arm for each link and pivotally connected to the other end thereof and operatively associated with the first mentioned of the link connected doors for simultaneous movement of all doors. 100
